[57] **CLAIM**

The ornamental design for a dog comfort station, as shown and described.

DESCRIPTION

FIG. 1 is a perspective view of a dog comfort station, showing my new design;

FIG. 2 is a front elevational view;

FIG. 3 is a left side elevational view;

FIG. 4 is a right side elevational view;

FIG. 5 is a rear elevational view;

FIG. 6 is a top plan view;

FIG. 7 is a bottom plan view; and

FIG. 8 is a rear elevational view.

The broken lines in FIG. 8 merely illustrate the environment and form no part of the design.

FIG. 5.

FIG. 6.

FIG. 7.

FIG. 8.
